A. DRAKE.
EXPLOSIVE GAS ENGINE.

No. 12,715.

Patented Apr. 17, 1855.

Inventor

A. Drake

UNITED STATES PATENT OFFICE.

ALFRED DRAKE, OF PHILADELPHIA, PENNSYLVANIA.

IMPROVEMENT IN EXPLOSIVE-GAS ENGINES.

Specification forming part of Letters Patent No. 12,715, dated April 17, 1855.

To all whom it may concern:

Be it known that I, ALFRED DRAKE, of the city of Philadelphia, and State of Pennsylvania, have invented new and useful improvements in an engine to be actuated by the expansive force of explosive mixtures of oxygen gas or atmospheric air with hydrogen gas, hydrocarbons, &c., of which the following is a specification.

The first part of my improvement and the principal distinctive feature of my engine is an improved apparatus for igniting the explosive mixture of gases in the cylinder. The second part of my improvement embraces an improved arrangement for cooling the working parts of the engine; and I do hereby declare that the following is a full, clear, and exact description thereof, reference being had to the annexed drawings, making a part of this specification, in which—

Figure 1 represents a top view of my improved engine. Fig. 2 is a vertical longitudinal section through the cylinder-piston and piston-rod and showing the position of the ignition apparatus and the arrangement for cooling the parts. Fig. 3 is a side view of the air-pump and valves detached. Fig. 4 is a view of the top of the ignition apparatus removed. Fig. 5 is a vertical section through the ignition apparatus. Figs. 6, 7, and 8 represent the detached parts composing the ignition apparatus.

A B C D, Fig. 2, represent a section of the cylinder of the gas-engine constructed of metal in a manner similar to the cylinder of an ordinary steam-engine.

K L represent the piston made hollow, so as to contain water for cooling.

M N represent the piston-rod, also made hollow, so as to supply the piston with a constant supply of cool water and to allow the heated water to escape.

I I I I represent a hollow metallic jacket surrounding the cylinder and communicating by the tubes *t* and *t* with the piston and piston-rod, so as to maintain a constant circulation of cool water through the jacket, piston, and piston-rod, in the manner hereinafter described.

O O' is a condensing air-pump operated by means of an arm *p p'*, attached to the piston-rod. There are two apertures at the receiving end of the pump *r* and *r'*. *r'* opens to

external atmosphere. The opening *r* is connected with the gasometer or reservoir containing the hydrogen or hydrocarbon gas. A third opening is connected with the tube *r''* passing down to the reservoir R of combined gases.

The cylinder is connected by tubes with any reservoir of hydrocarbon gas and with openings to the atmosphere, arranged and operating as described hereinafter.

The respective ejection and induction valves are operated by a rock shaft and an eccentric, as in the ordinary steam-engine, and it is not therefore deemed necessary to refer minutely to these parts nor to the manner of connecting the piston-rod with the crank.

In the construction of my improved engine the general arrangements of the steam-engine are made use of, the valves being so placed as to tighten under the pressure within the cylinder, the induction-valves closing on the admission of an adequate supply of the explosive mixture at any determined point—say at one-fourth or one-fifth of the stroke. When the proper charge is taken into the cylinder, the induction-valve is closed, and the continued travel of the piston uncovers an opening in the cylinder *e* and *e'* communicating with the ignition apparatus.

The ignition apparatus is shown on the outside at *a b* and *a' b'* in Fig. 1, and at *a b c d* and *a' b' c' d'* in Fig. 2 and in Figs. 5, 6, 7, and 8, and consists of five pieces. *a b c d* and *a' b' c' d'* are precisely alike, and the description of the former will serve for both.

a b c d is a metal box standing about three inches high, with an internal opening of one and a quarter inch diameter. One of these boxes is bolted to the cylinder of the engine by the flanges *f f* over corresponding openings near each end of the cylinder. The upper part of the interior of this box *g g' h h'*, Fig. 5, is tapered slightly so as to form a tight junction with the piece *k k'*, which is one and three-quarters inch long, and is also made correspondingly tapering on the outer side.

To the piece *k k'* is attached the piece *S S'*. This is a thimble-shaped piece of hard cast-iron or other suitable metal two and a quarter inches long, three-quarters of an inch internal diameter, and one-sixteenth of an inch thick. The lower extremity *S'* juts into

the openings through the cylinder at e and e' . The piece k k' has a shoulder by which it rests upon and is secured to the body of the box a b c d .

At u is an aperture communicating with the interior of the thimble S S' S'' , half an inch in diameter, for the purpose of firing the jet of gases introduced through the blow-pipe y y' .

Upon k k' is secured a cap v v' , having on its upper side an offset, to which is attached the pipe r''' , conveying mixed gases from the reservoir R . To the under side of v v' is attached a tube y y' , which is made of hard cast-iron or other suitable material two and three-fourths inches long, three-eighths of an inch thick, and one-eighth of an inch in diameter, entering into the interior of S S' S'' and forms the blow-pipe for the inflamed gases.

O O' is an air-pump for forcing into the reservoir R , above described, a proper supply of mixed gases for the jet of the blow-pipe and for the starting of the engine. This supply is obtained in proper proportion by having the valves to both the ignition supply-pump and to the supply-pipe of the engine arranged so as to cover at the same time an opening r' to the atmosphere, and also the opening r of the pipe conveying the gas. This last pipe has a cock so adjusted as to admit a definite and proper supply of gas. For instance, in using ordinary bicarbureted hydrogen gas, about one volume of the gas is required to make a saturating-mixture with nine volumes of atmospheric air, and if the cock is adjusted so as to admit only one-tenth of the capacity of the joint openings under the valve a mixture is obtained which will insure the greatest power. The power or force of the engine may be reduced and regulated by a throttle-valve in the supply-pipe of the engine.

In starting the engine it is necessary to throw into the reservoir R , by a pump worked by hand, a sufficient quantity of air and gas to heat up the igniting apparatus, and it is necessary, also, that the piston of the engine be so placed as to expose the extremity S' of one of the ignitors. The cock l , attached to the supply-pipe of the blow-pipe, is then opened and a taper is applied to the opening u , and thus the trail is fired. The flame of the compound blow-pipe being directed against S' , raises the temperature of the ignitor at S' to the exploding point. The first motion of the piston of the engine is then given by throwing into the cylinder from the

reservoir R an explosive mixture, which, being fired by the ignitor, impels the piston. The engine now being in action, the piston in its travel draws in a charge through the induction-valve at the opposite end. This charge is in turn fired by the exposed ignitor at the opposite end, and thus a reciprocating action is maintained.

In an engine impelled by gaseous matter inflamed in the cylinder it is necessary to keep down an impervious degree of temperature and also to be able to use requisite lubrication. These objects are effected by surrounding the cylinder with an external casting or jacket I I I I , as above described, and by causing a constant stream of water to pass as follows: The water from any convenient reservoir or source is admitted into the jacket I I I I through the aperture 1 . The water then fills the jacket I I I I surrounding the cylinder and passes out at the upper part of the jacket through the tubes t t into the fixed tube P P' , on which the piston-rod M N slides, and the water fills up the piston-rod M N . The water thence passes into the piston K L , through the aperture 3 , circulates therein, and returns back into the piston-rod through the aperture 4 , and finally escapes from the piston-rod at the aperture 5 . A small stuffing-box x x' , packed with asbestos or fine wire, is placed in the extremity of the piston-rod, so as to surround the tube and form a tight joint at that point. By this peculiar arrangement and combination of jacket, hollow piston, and piston-rod the temperature is kept at a lower and more uniform point than in any previously-constructed gas-engine, and thorough lubrication therefor can be obtained.

Having thus described my improved gas-engine, I do not wish to claim the employment or application of explosive admixtures of gases to engines; but

What I do desire to claim as my invention, and secure by Letters Patent, is

1. The igniting apparatus composed of the thimble S S' S'' and the interior tube or blow-pipe y y' , arranged and operating substantially as hereinbefore described.

2. The arrangement and combination of the hollow piston-rod, piston, and jacket surrounding the cylinder for the purpose of maintaining a constant circulation of water for cooling, substantially as hereinbefore described.

ALFRED DRAKE.
